UNITED STATES PATENT OFFICE

2,442,222

PRESSER FOOT

Frederick J. Uccellini, Norwalk, Conn.

Application February 18, 1947, Serial No. 729,262

3 Claims. (Cl. 112—43)

1

The present invention relates to a presser foot for use on sewing machines and particularly to liquid or lubricant applying means thereon.

Under some circumstances it is desired to apply a liquid or lubricant to the surface of the material before it passes under the presser foot. For example, when rubber or tacky material is being stitched a lubricant may be applied to the surface of the material to aid the material, as it advances, to slide under the presser foot as it is being fed.

Heretofore, the means for applying the liquid have been either inefficient or so cumbersome that they would interfere with the operator or the material during the sewing operation.

The present invention overcomes these difficulties by providing a presser foot having a liquid or lubricant applying means which operates efficiently over long periods of time and which has no projecting parts to interfere with the sewing operation.

This is accomplished by building a suitable applicator and supply passages therefor into the presser foot and connecting the supply passages in the presser foot to a reservoir for the material to be applied. It is presently preferred to use a hollow presser bar as the reservoir and to connect the bottom of the bar to the supply passage in the presser foot so that none of the component parts of the supply means lie outside of these elements to interfere with the manipulation of the fabric or material or the sewing operation.

Other features and advantages will be apparent from the specification and claims when considered in connection with the drawings in which:

Figure 1 is a side view of the presser foot of the present invention.

Fig. 2 is a detail view, partly in section, showing the passages and reservoir.

Fig. 3 is a section taken along line 3—3 of Fig. 2.

As shown in the drawings the presser bar 10 is slidably mounted in the head 11 in the usual manner and a presser foot 12 having a presser bar receiving sleeve 12a is secured to the bottom thereof by a set screw 13 or any other suitable means. The presser foot is normally urged by the presser bar into engagement with the top of the material to be stitched (not shown) and maintains it in position to be engaged by the usual feed dog 14 of the sewing machine and advanced and held thereby as it is stitched by the needle 15 carried by the needle bar 16 reciprocating in the head 11 and passing through the aperture 17 in the presser foot.

2

The present invention provides means on the presser foot for applying a coating to the material being sewn as it passes under the presser foot. The nature of the coating may vary in accordance with the requirements of the particular operation. For example, if the material being sewn is artificial leather or a plastic material which is sticky, a lubricant for the material is applied to the surface to permit it to slide readily under the presser foot.

This is accomplished by providing the usual upturned tip 12b of the presser foot with a downwardly facing recess or socket 18 in which is mounted an applicator 19 in the form of a wick or brush which projects into wiping engagement with the upper surface of the material being sewn. As shown in Fig. 3 the applicator is preferably disposed on the line of sewing, i. e., the line passing through the needle aperture in the presser foot and the center of the presser bar along which the feed dog moves the material, and is of such a width as to effectively spread a sufficient amount of lubricant on the surface passing under the presser foot. The lubricant which may be oil, grease or water, depending upon the material being sewn, is fed from a reservoir to the recess containing the applicator through passages or ducts 20 formed in the body of the presser foot and extending from the recess to the bore in sleeve 12a. The lubricant is transferred from the recess through the applicator to the surface by capillary action or by gravity.

In the illustrated form of the invention the presser bar is made in the form of a hollow tubular member and forms the reservoir 21 for the lubricant. The end of the tubular bar fits within the sleeve 12a of the presser foot and communicates with the ducts 20 therein so that lubricant stored in the reservoir will feed through the ducts 20 under the pressure of the head of lubricant in the reservoir. The reservoir may be conveniently replenished through the top of the presser bar which is closed by a threaded plug.

The foregoing structure it will be seen provides for the storing of an adequate supply of lubricant and for distributing it evenly over the surface of the material being sewn as required without any projecting means which will interfere with the manipulation of the material being sewn or with the operator during the sewing operation.

Variations and modifications may be made within the scope of this invention and portions of the improvements may be used without others.

I claim:

1. A presser foot mechanism for sewing machines comprising a presser bar; a presser foot mounted on the lower end of the presser bar and provided with an upwardly extended tip, said tip having a recess adjacent the end; and a lubricant-applying brush secured therein to project from the foot and into engagement with the material adapted to be fed under the foot, said presser bar being hollow and forming a lubricant reservoir and said presser foot having ducts formed within the foot and extending from the reservoir to the recess to supply lubricant to the brush.

2. A presser foot mechanism for sewing machines comprising a presser bar; a presser foot mounted on the lower end of the presser bar and provided with an upwardly extended tip, said tip having a recess adjacent the end; a lubricant-applying member secured therein to project from the foot and into engagement with the material in advance of the needle; and a lubricant reservoir for supplying lubricant thereto, said presser foot having passages therein which bypass the needle and extend from the reservoir to the lubricant-applying member to supply lubricant thereto.

3. A presser foot mechanism for sewing machines comprising a presser bar; a presser foot mounted on the lower end and provided with an upwardly extended tip, said tip having a downwardly facing socket adjacent the end; and a liquid applicator secured therein to project from the foot and into engagement with the material, said presser bar being hollow and forming a liquid reservoir and said presser foot having ducts extending from the reservoir to the applicator to supply liquid thereto.
